UNITED STATES PATENT OFFICE

FREDERICK H. LUENSE, OF CHICAGO, ILLINOIS

WINDING MECHANISM FOR TIME-CLOCK STAMPS

Application filed February 12, 1927. Serial No. 167,637.

My invention relates to time stamps. It relates more particularly to stamps controlled by clock mechanisms, in which the driving spring thereof is wound by the 5 stamping lever.

One of the objects of my invention is to produce an improved and simplified time stamp.

Another object is to wind the clock spring 10 of such a stamp automatically so that during operation it will always have substantially the same tension.

Another object is to provide a time stamp in which the clock mechanism spring is 15 wound automatically but can also be wound by hand.

Another object is to prevent over-winding of the time stamp clock spring.

Other objects and features will appear 20 from the detailed description taken with the accompanying drawings in which

Fig. 1 is a side elevation partly in section, of one form of time stamp embodying the features of my invention;

25 Fig. 2 is a sectional view taken on the line 2—2 of Fig. 1, looking in the direction of the arrows;

Fig. 3. is a sectional view on line 3—3 of Fig. 2;

30 Fig. 4 is a section on line 4—4 of Fig. 3, showing the clock spring in elevation, and

Fig. 5 is a view, partially in section, of a modified form of spring winding means.

Figs. 1 to 4 inclusive, relate to clocks in 35 which the spring drum unwinds in the same direction in which it is wound up. This is the usual arrangement in the better clock mechanisms, and represents the kind of clock mechanism which would probably be used in 40 most cases. Fig. 5 shows the invention applied to a clock in which the driving spring unwinds in a direction opposite to that in which it is wound. This is for illustrative purposes only, as either may be employed in- 45 dependent of the type of clock mechanism.

In accomplishing the invention a ratchet wheel is provided on the winding arbor of the clock mechanism driving spring, and a spring pressed pawl is adapted to engage and drive 50 the ratchet wheel to wind the spring. The

stamping lever has an operable resilient connection with the spring pressed pawl, so that each operation of the stamping lever is adapted to increase the spring tension slightly. When the spring is tensioned a predetermined amount, the resilient portion of the winding mechanism lengthens sufficiently to prevent further winding of the clock spring, until the tension thereof has been decreased. 55

The main embodiment will be described 60 first in the drawings the conventional portions of the stamp and clock mechanism are shown somewhat diagrammatically since the present invention does not necessarily contemplate modifying them. The stamp has 65 the usual outer casing or housing 10, with a suitable clock mechanism 11, adjustable type 12, and a driving connection 13 from the clock mechanism to the time stamping or adjustable type. A dial face 14 is provided in 70 the top of the housing, and the usual clock hands 16 on the dial face are also driven by driving connection 13 through head gearing 15. Any usual provision for inking or otherwise fitting type 12 for recording time, etc. 75 is provided and a stamping lever 17 provides the necessary impressing force when a hand knob 18 is engaged and depressed. The lever is pivoted to a transverse pin 19, and is equipped with an end extension 21 the purpose of which will be hereinafter described. 80

Clock mechanism 11 is mounted between transverse vertical mounting plates 22 and 23 which may constitute integral parts of housing 10 or may be separable therefrom. The 85 portions of the clock mechanism which might be considered requisite to understand the present invention are the spring winding arbor 24, shown as a shaft to which main spring 25 has its inner end secured. Keyed or otherwise fixed to the arbor is a ratchet wheel 26 having in engagement therewith a pawl 27 pressed by a spring 28 against the ratchet wheel. This ratchet and pawl retain 90 the tension of the spring, and have a function to perform during the winding operation 95 which will be described.

The outside end of the main spring is secured to spring drum 29, a pin 31 on the outside of the drum effecting the connection. A 100

spur gear 32 formed integral with the drum meshes with a larger gear 33 which is mounted on connecting shaft 13. The train of gears to the escapement mechanism, and the escapement itself are not shown, but the train of gears is from spring gear 32.

Outside of the rear mounting plate a winding ratchet wheel 34 is secured to the winding arbor. A bifurcated reciprocal lever 35 is 10 rotatably mounted on the arbor, with one of its bifurcations on each side of the winding ratchet. A pawl 36 is pivotally secured between the bifurcations of the lever on a mounting pin 37, and is urged against the 15 ratchet wheel by a spring 38. A tension spring 39 is secured between lever 35 and the end extension of the stamping lever. The lower end hook of the spring is secured directly in an aperture in the pawl carrying 20 lever, while the upper hook is linked to a screw eye 41. Screw eye 41 extends upwardly into a vertical bore in the stamping lever end extension, and is secured therein by a thumb nut 42. By this means the length of 25 the connection and the tension of spring 39 between the pawl carrying lever and the stamping lever is adjusted. Thus the extent to which the driving spring is wound may be varied. For instance, a stamp may be used 30 freely throughout each day in which case less tension of the driving spring is required than where a stamp may be used less, as for example a day or two apart.

To return the stamping lever to normal position after operation, a tension spring 43 is 35 provided. In the drawing it is shown connected between the pawl lever and the base of housing 10. In this position it not only returns the stamping lever to normal position, but also serves to keep the spring winding portions of the mechanism in proper position. They do not depend on gravity alone 40 to return to position after a spring winding action.

45 It is conceivable that it may be desirable to wind the clock spring by hand. To facilitate such an operation the end 44 of the arbor is formed angularly, and the housing or casing adjacent thereto has a key opening 45 therein. A suitably designed key projected through the housing at the key opening will engage the end of the arbor, and the clock can be wound by hand.

In the modification shown in Fig. 5 a pair 55 of telescoping members 51 and 52 are provided, held together in telescoped relation by a spring 53. The lower end of member 52 is confined in a guide 54, and the upper one of the telescoping members has a threaded portion 55 of smaller diameter, extending 60 through the end of the stamping lever and secured thereto by a thumb nut 56 which may be adjusted to vary the effective length of the connection between the stamping lever and 65 the clock mechanism, as well as the normal

tension of spring 53 to determine, as in the previous embodiment, the extent to which the spring 25 is wound.

A pawl 58 is mounted on member 52 and is pressed toward a ratchet wheel 57 by a spring 59, also secured on the telescoping member. Ratchet wheel 57 is secured to the winding arbor, and hence vertical reciprocal movement of the telescoping members assembly results in the pawl engaging the teeth of the ratchet wheel and a partial rotating of the winding arbor and consequently winding the spring. When the clock spring tension is greater than the strength of spring 53 the telescoping members will slide apart slightly at 80 each operation of the stamping lever, until such time as the clock spring has become sufficiently unwound so that spring 53 can again hold the telescoping members together.

In this embodiment a separate spring or other suitable means (not shown) is provided to return the stamping lever. The other portions of the mechanism may be the same as in the embodiment previously described.

In Fig. 5 the parts similar to those shown 90 in the other figures, bear the same reference characters.

In the operation of the time stamp the paper or other article to be stamped is placed 95 between the type and the type engaging end of the stamping lever. The lever is depressed and the paper stamped in the usual way. Concomitantly the end extension of the lever is raised and the winding ratchet operated 100 through the connecting spring and other mechanism. At each depression of the stamping lever the spring is wound slightly, until the tension of the clock spring overcomes the ratchet operating spring, when the movement of the winding ratchet will not be sufficient to 105 move the spring arbor a distance represented by one tooth on the tension retaining ratchet and the clock spring is not wound any further.

The drawings show the tension retaining 110 ratchet wheel furnished with fewer teeth than the winding ratchet wheel. This means that the retaining ratchet wheel will have larger teeth than the winding ratchet wheel, or be smaller in size, so that one tooth represents a greater part of the circular arc. This construction is optional, as good results can be 115 obtained if the number of teeth is the same.

With my improved self winding stamp the 120 clock mechanism is always running, and there is no necessity of attempting to remember to wind the clock. It does everything that electrically wound stamps do, but is much more economical. Furthermore, it is easily portable, since it does not have the cord, concomitant to electrical clocks, and which makes 125 it necessary to keep such clocks more or less permanently in one position. Furthermore, since the spring has practically constant tension, a clock mechanism of more simple and durable construction can be used, since it is 130

not necessary for it to be so nicely balanced. I do not wish to limit myself to any of the details previously described, but what I claim as new and desire to protect by Letters Patent of the United States is:—

5. 1. In a time stamp, a clock mechanism having an operating spring mounted upon a winding arbor, a ratchet wheel secured to said arbor, a pair of telescoping members having a spring connection therebetween, a ratchet wheel engaging pawl on one of said members, a pivoted stamping lever having an end extension beyond the pivot point thereof, and an adjustable connection between said extension and one of the telescoping members. 10
10. 2. In a time stamp of the character described, a spring operated clock mechanism, type controlled and set in printing position by said clock mechanism, a horizontal lever with a horizontal pivot intermediate the ends thereof so as a result in a type impressing stamping lever adapted to be pressed downwardly to make an impression and a rear spring winding extension adapted to be raised upwardly in response to the impressing of said stamping lever, a resilient connection from said lever extension to said clock mechanism to wind the spring and at the same time prevent overwinding thereof due to the resilient character of the connection, and means for regulating the tension of said resilient connection thereby to govern the tension to which the clock spring will be wound. 15
15. 3. In a time stamp of the character described, a spring operated clock mechanism, type controlled and set in printing position by said clock mechanism, a horizontal lever with a horizontal pivot intermediate the ends thereof so as to result in a type impressing stamping lever adapted to be pressed downwardly to make an impression and a rear spring winding extension adapted to be raised upwardly in response to the impressing of said stamping lever, a lever having a connection to wind the clock mechanism, a coil spring secured to said lever and having a threaded pin at the other end thereof, said threaded pin extending through a vertical aperture in the end of the stamping lever extension, and a thumb nut on said threaded pin adapted to be turned to regulate the tension of said spring. 20
20. 4. In a time stamp of the character described, a spring operated clock mechanism having the usual main spring with a drum housing therefor, and an arbor extending through the center thereof, the ends of the spring being connected to said drum and arbor, a plurality of type wheels, a connection from the movable drum to the type wheels to drive and set the same in printing position in accordance with the time of day, a pawl stopped ratchet wheel on said arbor, a second ratchet wheel on said arbor, a lever having one end thereof loosely secured to 25
25. said arbor, a pawl on said lever engaging said second ratchet wheel, a horizontal stamping lever with a horizontal pivot intermediate the ends thereof so as to result in a type impressing stamping lever, and a rear extension therefrom, and a resilient connection between said lever and said stamping lever extension. 30
30. 5. In a time stamp of the character described, a spring operated clock mechanism having the usual main spring with a drum housing therefor, and an arbor extending through the center thereof, the ends of the spring being connected to said drum and arbor, a plurality of type wheels, a connection from the movable drum to the type wheels to drive and set the same in printing position in accordance with the time of day, a pawl stopped ratchet wheel on said arbor, a second ratchet wheel on said arbor, a lever having one end thereof loosely secured to 35
35. said arbor, a pawl on said lever engaging said second ratchet wheel, a horizontal stamping lever with a horizontal pivot intermediate the ends thereof so as to result in a type impressing stamping lever, and a rear extension therefrom, a spring having one end secured to said lever and the other end secured to a threaded pin, said threaded pin extending through a vertical opening in said stamping lever extension, and a thumb nut secured to said threaded pin adapted to be turned to control the tension of said spring. 40
40. 6. In a time stamp of the character described, a spring operated clock mechanism having the usual main spring with a drum housing therefor, and an arbor extending through the center thereof, the ends of the spring being connected to said drum and arbor, a plurality of type wheels, a connection from the movable drum to the type wheels to drive and set the same in printing position in accordance with the time of day, a pawl stopped ratchet wheel on said arbor having relatively few teeth, a second ratchet wheel on said arbor having a greater number of teeth, a lever having one end thereof loosely secured to said arbor, a pawl on said second ratchet wheel, a horizontal stamping lever with a horizontal pivot intermediate the ends thereof so as to result in a type impressing stamping lever, and a rear extension therefrom, and a resilient connection between said lever and said stamping lever extension. 45
45. 7. In a time stamp, a clock mechanism having a winding arbor, an operating spring mounted thereon, a ratchet wheel secured on the winding arbor, a reciprocable lever loosely pivoted on said arbor, a spring pressed pawl on said lever engaging said ratchet wheel, a pivoted stamping lever having an end extension beyond the pivot point thereof, a resilient connection between said extension and reciprocable lever for winding said arbor spring when the stamping lever is operated, 50
50. 8. In a time stamp, a clock mechanism having a winding arbor, an operating spring mounted thereon, a ratchet wheel secured on the winding arbor, a reciprocable lever loosely pivoted on said arbor, a spring pressed pawl on said lever engaging said ratchet wheel, a pivoted stamping lever having an end extension beyond the pivot point thereof, a resilient connection between said extension and reciprocable lever for winding said arbor spring when the stamping lever is operated, 55
55. 9. In a time stamp, a clock mechanism having a winding arbor, an operating spring mounted thereon, a ratchet wheel secured on the winding arbor, a reciprocable lever loosely pivoted on said arbor, a spring pressed pawl on said lever engaging said ratchet wheel, a pivoted stamping lever having an end extension beyond the pivot point thereof, a resilient connection between said extension and reciprocable lever for winding said arbor spring when the stamping lever is operated, 60
60. 10. In a time stamp, a clock mechanism having a winding arbor, an operating spring mounted thereon, a ratchet wheel secured on the winding arbor, a reciprocable lever loosely pivoted on said arbor, a spring pressed pawl on said lever engaging said ratchet wheel, a pivoted stamping lever having an end extension beyond the pivot point thereof, a resilient connection between said extension and reciprocable lever for winding said arbor spring when the stamping lever is operated, 65

and a ratchet and pawl associated with the winding arbor for maintaining the same in wound condition when the reciprocable lever is withdrawn, said winding ratchet having a number of teeth different from the number 5 on the tension maintaining ratchet.

In witness whereof, I hereunto subscribe my name this 8th day of February, 1927.

FREDERICK H. LUENSE.
